UNITED STATES PATENT OFFICE.

FREDERIC K. PLYMPTON, OF WELLESLEY, MASSACHUSETTS, ASSIGNOR TO PLYMPTON MANUFACTURING COMPANY, OF BOSTON, MASSACHUSETTS, A CORPORATION OF MASSACHUSETTS.

BOTTLE-CLOSURE.

1,159,533.

Specification of Letters Patent.

Patented Nov. 9, 1915.

Application filed July 1, 1909. Serial No. 505,405.

To all whom it may concern:

Be it known that I, FREDERIC K. PLYMPTON, a citizen of the United States, residing at Wellesley, in the county of Norfolk, State 5 of Massachusetts, have invented a certain new and useful Improvement in Bottle-Closures, of which the following is a specification, reference being had therein to the accompanying drawings.

10 Objection lies to the present mode of sealing bottles and jars containing milk and cream, by means of disks of paper-material pressed down within the mouths of such bottles and jars into place in connection with 15 seats that are formed within such mouths, by reason of the fact that waste milk, dirt, pieces of ice, and water, become lodged in the open spaces above such disks, and drop into the contents of the bottles when the 20 disks are withdrawn, thereby contaminating the said contents. The disks are difficult of removal, and attempts at removal are attended often by the ejection and loss of portions of the contents, sometimes in jets or 25 streams which spurt out upon one's clothing and upon the surroundings.

Various attempts have been made to provide caps or closures adapted to completely inclose and cover the mouth of a bottle or 30 jar, but none of such caps or closures heretofore proposed has gone into general or extensive use. Dealers in milk cannot afford to use closures, or will not, unless able to procure them at an exceedingly low cost, the 35 cost, for instance, in the case of the simple disks aforesaid being a very few cents per thousand. For such reason, and others, it is not practicable to use sheet-metal closures of the character employed for bottles containing beer and other beverages. Such closures require a special instrument for their 40 removal. The large size of the mouth of a milk-bottle or jar precludes the use of caps or covers composed of sheet-metal or other 45 comparatively expensive materials, especially if the cost of manufacture be increased by the addition of cork or other packing to avoid leakage. The problem which I have aimed to solve by my present invention, 50 therefore, has been to adopt an efficient simple construction free from the drawbacks of the disks aforesaid, easy of removal without the employment of special instruments, containing only low-priced materials, inexpensive to make, and capable of being supplied

to milk-dealers at a small price per thousand.

My cap or closure is of flange-type, the flange fitting around the exterior of the rim of the mouth of the bottle or jar, and clasping the said exterior. 60

The invention resides more particularly in a cap or cover formed of non-metallic material, and having the flange thereof constructed to enable the same to expand slightly as the cap or cover is applied by forcing the flange downward outside the rim, and to then contract so as to take secure hold. 65

The invention consists, essentially, in a milk-bottle cap or cover of inexpensive 70 paper-material, stiffened cloth, or other suitable non-metallic material, having a resilient flange, which may be of reduced inside diameter at the free edge thereof, although this reduction in diameter is not necessary in

all embodiments of the invention, such flange having imparted thereto sufficient stiffness to enable it to be forced down into place upon the exterior of the rim of the mouth of a milk-bottle or jar, by means of an elastic constrictive reinforcing band. The said band strengthens and stiffens the flange so as to enable it to be forced down into place around the bottle mouth without collapsing or crushing. 75 In addition, it gives increased elasticity to the flange so that it will expand sufficiently to pass down over the rim of the bottle or jar and then contract to clasp properly its seat upon the exterior of the bottle mouth. The said cap or cover fits over and entirely covers the mouth of the bottle or jar, and the flange extends down around the rim, clasping with resilient action the periphery of the latter, so that when the cap or cover is in place said mouth is completely 80

protected and there is no pocket or space within the mouth, open above, to receive and hold waste milk, drippings of water, particles of ice and dirt, and germs, in readiness to drop into the bottle or jar on the removal of the cap or cover, to impair the contents, as is the case when the ordinary disk-shaped closure is employed. The rim of the bottle or jar being formed with an exterior bead, or with a peripheral groove at a short 85 distance below the top, the free edge of the flange of the cap or cover spreads or expands in being applied as it is forced down past the rim and the said bead, and it contracts below the bead or into the said groove, and 90

100

105

110

thereby firmly secures the cap or cover in place against accidental displacement.

The invention is illustrated in the drawings, in which,—

- 5 Figure 1 is an elevation of a cap or cover containing one embodiment of the invention. Fig. 2 shows in vertical section the upper portion of a bottle, with the said cap or cover applied thereto. Fig. 3 is an elevation
 10 of a cap or cover like that of Figs. 1 and 2, but having a slitted flange. Fig. 4 is an elevation of a cap or cover having a constrictive reinforcing band composed of a flat strip of spring material. Fig. 5 is an elevation
 15 of a cap or cover having a band composed of a corrugated strip of metal. Fig. 6 is a view in horizontal section on line 6, 6, of Fig. 5. Fig. 7 is an elevation of a cap or cover having a band of metal applied to the
 20 outside of its flange, the ring and flange both being corrugated. Fig. 8 is a view of the lower edge of the cap or cover of Fig. 7.

Having reference to the drawings,—the neck-portion of a milk-bottle is shown at 1, 25 in Fig. 2. The cap or cover in which the invention is embodied is shown at 2. The body-portion of the said cap or cover is of a diameter to cover the top of the rim of the mouth of the milk-bottle. The depending flange of the cap or cover is marked 3. The inward taper or contraction of the said flange toward its free edge is shown in Figs. 1 to 5, and 7. At 4, Figs. 1, 2 and 3, is a constrictive reinforcing band, applied to 30 the exterior of the said flange as aforesaid. This band is composed of cloth, in the form of the invention shown in Figs. 1 to 3, although a strip of suitable paper is employed by me in some instances instead of 35 cloth, and in the said figures it is attached to the exterior of the flange by adhesive material. The exterior bead or swell of the mouth-portion of the bottle is designated 5, its upper portion being rounded, and 6 is an 40 annular depression or groove around the neck just below the said bead or swell.

The interior diametrical measurement of the cap or cover at the lower edge of the flange thereof may be slightly less than the 45 extreme diameter of the bead or swell, as in the drawings. A cap or cover embodying the invention is intended to require a little force to be exerted upon the cap or cover in pressing it upon the mouth-portion of the bottle. As such force is applied, pushing the cap or cover downward, the rounded upper portion of the bead or swell expands the lower portion of the flange, sufficiently to permit such portion to pass down below 50 the largest diameter of the bead or swell, whereupon the free edge of the flange contracts upon the lower portion of the bead or swell, or into the groove or depression below the bead or swell. The flange then 55 clasps around the bead or swell tightly, as

shown in Fig. 2, and securely holds the cap or cover in place. On the proper application of sufficient force in the direction to lift the cap or cover from the bottle-mouth, the flange stretches or expands so as to permit it to be drawn upward past the bead or swell, enabling the removal of the cap or cover to be readily effected at will. The cap or cover may subsequently be replaced.

Below the groove or depression 6 the neck-portion of the bottle may be enlarged in diameter at 7, forming a shoulder which projects outward farther than the bead or swell, and also somewhat beyond the flange of the cap or cover when the latter is in place. The purpose of this is to furnish a handhold to support the bottle without danger of slipping when the neck is taken hold of in lifting the bottle, and to safeguard against accidental dislodgment of the cap or cover by one's fingers if the latter should be moved or should slip upward along the neck-portion while clasping the latter. The said enlargement shields the flange of the cap or cover by causing the fingers to pass up outside of the flange, usually without contact with the latter.

The inward contraction of the flange is advantageous in that it provides for more effectually holding the flanged caps or covers to the mouth-portions of the bottles to which they are applied in being used; and without the elastic constrictive reinforcing band the flanges of the different caps or covers would lack the requisite elasticity and the capacity to contract after being expanded in passing over the beads or swells of such mouth-portions.

When the cap or cover is composed of heavy or stiff material the flange may be 105 slitted as at 2^a, 2^a, 2^a, in Fig. 3 to facilitate expansion of the same in being applied to the mouth of a bottle.

The constrictive band may be composed of a strip of spring metal, as at 4^a in Fig. 4, 110 which is bent around the flange and secured thereto by punching portions of the metal into the flange, as at 4^b, 4^b. The ends of the strip are left unconnected with each other, so that the band constitutes in effect 115 a split ring and is free to expand and contract.

Figs. 5 and 6 show a band 4^c of corrugated spring metal secured to the flange by punching portions of the band into the flange, as at 4^d, 4^d. In this case the band stretches in part by the straightening out of the corrugations, and afterward contracts. The meeting ends of the band are shown at 4^e.

Figs. 7 and 8 show a band of metal 4^f applied to the flange 3, both the band and the flange at its lower edge being corrugated to give capacity to stretch and contract.

As will be apparent, I am enabled to furnish caps or covers made in accordance with

my invention at a very low price, while closures composed of metal would be impracticable on account of the large amount of material required in a single closure, and 5 the prohibitive high price.

It will be observed that in all the forms of the invention herein shown the band is composed of a flat strip of material and lies upon the outer surface of the flange of the 10 cap.

What is claimed is:—

1. A bottle closure comprising a flanged cap of flexible non-metallic material having combined with its depending flange a 15 wide elastic band which stiffens said flange vertically to enable it to be forced down into place around the bottle mouth without crushing, allows it to expand in passing over an enlargement of the bottle-mouth,

and constricts it around its seat upon the 20 bottle-mouth.

2. A bottle closure comprising a flanged cap of flexible non-metallic material having combined with its depending flange an elastic flat strip of metal which constitutes 25 a vertical stiffening for said flange enabling it to be pushed down into place around the bottle-mouth without collapsing, the said band constructed to allow the said flange to expand in passing over an enlargement of 30 the bottle-mouth, and to constrict the flange around its seat upon the bottle-mouth.

In testimony whereof I affix my signature in presence of two witnesses.

FREDERIC K. PLYMPTON.
